FLEXIBLE SHAFT MACHINE

Arthur W. Mall, Flossmoor, Ill., assignor to Mall
Tool Company, Chicago, Ill., a corporation of
Illinois

Application April 1, 1946, Serial No. 658,828

4 Claims. (Cl. 318—9)

1

This invention relates to flexible shaft machines wherein the working tool is remote from the power unit which actuates the tool, said tool being driven by a flexible power transmitting shaft. The general object of this invention is to provide remote control means for controlling the speed unit and/or for starting and stopping the power unit.

Another object of my invention is to provide improved means for quickly detaching the shafting from either the power unit or the working tool actuated by the power unit, said means being also incorporated in the general objective of controlling the speed or the starting and stopping of the power unit.

Other objects and advantages will become apparent upon reading the following specification and upon examination of the drawings in which:

Fig. 1 is a side elevational view of my invention as used with a gasoline engine in conjunction with a concrete vibrator tool;

Fig. 2 shows a different type of working tool;

Fig. 3 is a detail plan view of the remote control actuating means;

Fig. 4 is a detailed view of my invention as used in connection with the actuation of the switch of an electric motor;

Fig. 5 is a sectional view showing the preferred form of my invention;

Fig. 6 is a detailed sectional view of the working tool end of my machine;

Fig. 7 is a detailed view of the coupling device as shown in Figs. 5 and 6;

Fig. 8 is a fragmentary detailed view taken from Fig. 7;

Fig. 9 is a detailed sectional view showing a modification of my coupling means;

Fig. 10 is a detailed sectional view showing another modification of my coupling means;

Fig. 11 is a sectional end view taken on line 11—11 of Fig. 10.

In general, my invention consists of a power unit A, which may be either a gasoline engine, electric motor or some other type of power transmitting unit. A flexible shaft B is driven by the power unit A and transmits rotative power to the working tool C. A flexible housing D encases the flexible shaft B and serves as a bearing for same.

In the preferred embodiment of my invention as shown best in Figs. 1, 3, 5 and 6 I have shown the general features of my invention. Referring to Fig. 5, the power unit is provided at its forward end with a casing 2 which forms part of the entire transmission housing. The driving shaft

which is directly connected to the engine shaft 3 transmits rotative motion to the flexible shaft B. Rigidly secured to the casing 2 is a cover 4 having a cylindrical sleeve portion 5 extending outwardly therefrom. The outer end of sleeve portion 5 is turned down so as to be smaller in diameter than the inner end of said sleeve portion 5.

The flexible housing D may be comprised of an internal steel ribbon 6 helically wound to form a tube. Layers of rubber 7 and fabric 8 encase the flexible tube 6 and in combination with the flexible tube 6 form a composite flexible casing or housing referred to as D. The housing D and shaft B may be of any desired length. The housing D at each of its ends is provided with steel ferrules 9 and 9a, which are preferably secured to the housing D by being compressed into the housing D as shown at 10 and 11. In viewing Fig. 5 it will be seen that the inner end 12 of the ferrule 9 is rotatably received within sleeve portion 5 of the cover 4. One of the important features of my invention involves the rotation of the inner end of sleeve 9 within sleeve portion 5 as will be hereinafter more fully explained.

It will be noted that the drive shaft 3 has an inner bore 13 to receive the driving tip 14 of the flexible shaft B. It will be noted in viewing Fig. 5 that the driving tip 14 is broken in section for the purpose of showing the detail of the drive nut 15. The drive nut 15 is threaded onto the outer end of drive shaft 3 so as to be rigid and rotatable therewith. The drive nut 15 is provided with internal spline teeth 16 which mesh with the spline grooves 17 in the drive tip 14. Thus the drive tip 14 of flexible shaft B is removably inserted through the drive nut 15 and is driven by said drive nut 15. The drive tip 14 is, of course, rigidly secured to the flexible shaft B so as to be rotatable therewith.

A collar 18 rotatably and slidably encases the sleeve portion 5 of cover 4. A compression spring 19 bears at one end against an annular shoulder 20 of sleeve portion 5 and bears at the other end against the annular shoulder 21 of collar 18, thus urging collar 18 away from cover 4 in normal locking position as shown in Fig. 5. A removable lock ring 22 prevents collar 18 from becoming disengaged from sleeve 5. It will be noted that the inner end 12 of ferrule 9 is provided with an annular groove 23 shown only in cross section in Fig. 5. A steel ball 24 (of which there is preferably 4) when urged into the annular groove 23 prevents the ferrule 9 from being withdrawn out of the sleeve 5. It will be noted that the collar 18 is provided with an internally restricted bore

25 which bore provides a circular bearing surface forcing the steel balls 24 into the annular groove 23. When it is desired to withdraw ferrule 9 from sleeve 5 the collar 18 is manually moved toward cover 4 against the compression spring 19, whereupon the steel balls 24 are permitted to drop into the circular recess 26 in collar 18, permitting withdrawal of the ferrule 9 from sleeve 5. Likewise, when ferrule 9 is being inserted into sleeve 5, the collar 18 is also manually moved toward cover 5 so as to permit retraction of the steel balls 24 into recess 26, thereby allowing the inner end 12 of ferrule 9 to slide into the bore of sleeve 5. Thus it can be seen that the flexible shaft assembly, including shaft B and housing D, can be readily and quickly connected and disconnected from the power unit A.

Referring to Figs. 3 and 5, as previously pointed out, the ferrule 9 along with housing D are rotatably received by sleeve 5 so that the entire housing D is rotatable relative to power unit A. The importance in providing housing D to be rotatable relative to power unit A, is incorporated in my remote control actuating mechanism. Heretofore it has been customary in flexible shaft machines to control the speed of rotation of the working tool C by having a man stationed at the power unit to manually actuate the switch or throttle of the power unit. If there was only one man attending the flexible shaft machine it was necessary for him to control the speed or the stopping and starting of the working tool C by carrying said tool up to the power unit and then manually actuating the switch or throttle of the power unit. A very important feature of my invention is to eliminate the necessity of having a man stationed at the power unit or to eliminate the necessity of carrying the working tool up to the power unit by providing remote control means, operable from the working tool C itself for actuating the switch or throttle of the power unit. Said remote control means functions by merely manually rotating the housing D relative to the power unit A, which manual rotation of housing D can be accomplished at the remote end of said housing D where the working tool is located. In the prior art it has been known to use remote control means for actuating the switch or throttle of a power unit, said remote control devices being auxiliary to housing D, such as, for example, providing a wire or string which runs along the housing D externally thereof. These devices have generally proven to be inadvisable. It will be noted that my invention eliminates these auxiliary devices in that the flexible housing D, itself, is utilized as the remote control actuating device in addition to serving its normal function as a bearing for the flexible shaft B.

Referring to Figs. 3 and 5, as previously pointed out, it will be noted that the inner end 12 of ferrule 9 is rotatable within sleeve 5, the steel balls 24 riding on the circular surface 25 when housing D is rotated relative to transmission housing 2, said steel balls 24 being also free to ride in the annular groove 23 in ferrule 9. A lever arm 27 is rigidly secured to ferrule 9 by means of clamping device 28. A bell crank lever 29 is pivotally secured to housing 2 and has a bifurcated end 30 which receives the free end of lever 27. When lever 27 is actuated by the rotation of housing D the bell crank lever 29 is likewise actuated. A connecting rod 31 is pivotally connected at 32 to bell crank 29 and has a hook 33 at its opposite end which overhangs

throttle lever 34. A tension spring 35 is connected to one end of the throttle lever 34 and is also connected at its other end to an adjustable screw 36, said screw 36 being threaded into a lug 37 which is secured to the transmission housing. The spring normally tends to urge the throttle lever in engine idling direction. When it is desired to increase the speed of the engine, the housing D is rotated, overcoming the tension of spring 35.

Referring to Fig. 4, the rod 31—a is secured to the switch lever 34—a whereby to turn the switch on and off.

In Fig. 6, I have shown the working tool end 15 of my machine and it is important to note that the working tool is rotatable relative to housing D. This rotatability is accomplished in the same manner as the rotatability of housing D relative to housing 2 is accomplished, as heretofore described. Like reference numerals with the letter 20 a added, have been used to designate the various parts at the working tool end. The reason for rotation of the working tool relative to housing D arises from the fact that in the use of a tool 25 of the type shown in Figs. 2 and 6 the operator manually grasps the gripping portion 40 in one hand and the housing D in the other hand. It is therefore possible for the operator to rotate housing D with one hand, while holding the working tool C steady against the work.

Referring to Figs. 9 and 10, I have shown modified forms of my invention. In Fig. 9 the inner end 12b of ferrule 9b is provided with a radially outwardly extended circular lip 41 which is free 35 to move slightly within the space between an annular shoulder 42 and the outer end 43 of cover 2b, thereby permitting sleeve 12b to rotate within supporting collar 44. Collar 44 is threaded onto the hub portion 45 of cover 2b until it engages annular shoulder 46. Housing D is thus separated 40 from cover 2 by unscrewing collar 44.

In Fig. 10 the nose portion 12c of ferrule 9c encases the nose portion 48 of sleeve 49. A radially outwardly flared annular lip 49 and a removable 45 thrust washer 50 prevent ferrule 9c from becoming separated from sleeve 49. The distance between thrust washer 50 and annular shoulder 51 is sufficient to permit a slight movement of ferrule 9c relative to sleeve 49 thereby permitting 50 housing D to rotate relative to support sleeve 49. Sleeve 49 is threaded onto hub portion 50 of cover 2c and is supported thereby.

Having thus described my invention, what I claim is:

55 1. A machine comprising a driving unit comprising a stationary housing portion and a rotatable shaft therein, a flexible shaft unit connected to the driving unit and comprising a flexible casing and a flexible shaft, the flexible shaft 60 being operatively connected to the rotatable shaft of the driving unit, means connecting the flexible casing to the driving unit housing including means fixed with respect to the housing and means rotatable with respect to the housing, the 65 last named means being connected to the flexible casing so that the casing has relative rotary movement with respect to the housing, means for regulating the operation of the driving unit, and means associated with the flexible casing for 70 manipulating the regulating means in response to the movement of the casing.

2. A machine comprising a driving unit comprising a stationary housing portion and a rotatable shaft therein, a flexible shaft unit connected to the driving unit and comprising a flexi-

ble casing and a flexible shaft, the flexible shaft being operatively connected to the rotatable shaft of the driving unit, means removably connecting the flexible casing to the driving unit housing including means fixed with respect to the housing and means slidably movable with respect to the housing, the last named means being connected to the flexible casing so that the casing has relative sliding movement with respect to the housing, means for regulating the operation of the driving unit, and means associated with the flexible casing for manipulating the regulating means in response to the movement of the casing.

3. A machine comprising a power unit, a shaft driven by the power unit, a casing enclosing the shaft, a working tool operatively connected to the shaft for actuation thereby, the shaft being rotatable in the casing, means mounting the casing for rotation thereof independently of the shaft, means effective to change the speed of operation of the power unit, and means operatively connecting the casing to the change speed means so that the operating speed of the power unit may be changed upon rotation of the casing.

4. A machine comprising a driving unit comprising a stationary housing portion and a rotatable shaft therein, a flexible shaft unit connected to the driving unit and comprising a flexible casing and a flexible shaft, the flexible shaft

being operatively connected to the rotatable shaft of the driving unit, means connecting the flexible casing to the driving unit housing including means fixed with respect to the housing and means slidably movable with respect to the housing, the last named means being connected to the flexible casing so that the casing has relative sliding movement with respect to the housing, means for regulating the operation of the driving unit, and means associated with the flexible casing for manipulating the regulating means in response to the movement of the casing.
